UNITED STATES PATENT OFFICE.

LOUIS FREY, OF FOX LAKE, ILLINOIS, ASSIGNOR OF ONE-HALF TO DAVID T. STONE,
OF CHICAGO, ILLINOIS.

STUMP EXTRACTOR.

Application filed May 20, 1927. Serial No. 193,030.

This invention relates to certain novel improvements in stump extractors and is particularly adapted for the pulling of tree stumps in clearing land. The salient object 5 of my invention is to provide a stump extractor which will embody maximum flexibility in order that it may be used to pull stumps that are located in diversified positions.

A further object of the invention is to provide a device of the class described which may be readily transported.

A still further object of the invention is to provide a stump extractor which will be simple in construction and efficient in operation.

15 Other objects will appear hereinafter.

The invention consists in the novel combination and arrangement of parts to be hereinafter described and claimed.

The invention will be best understood by 20 reference to the accompanying drawings, showing the preferred form of construction and in which:

The preferred embodiment of my invention is illustrated in perspective elevation.

25 Referring to the drawing, it may be seen that I provide an axle construction 10 on which wheels 11 and 12 are rotatably mounted. Suitably secured to the axle structure 10 as at 16 and extending therefrom are a 30 pair of parallelly disposed arms 14 and 15. A separating block 17 is provided between the arms 14 and 15 adjacent the axle structure 10 in order to separate said arms and at the opposite ends, the mid-point of a pull bar 18 35 is mounted between the arms 14 and 15 for pivotal movement about the fixed pivot 19 which serves to secure the pull bar 18 in position and which holds this end of the arms 14 and 15 together.

40 An anchor structure is provided which in the present instance is comprised of cables 20 and 21 and which are secured to the arm 14 adjacent the axle structure 10. The cables 20 and 21 are adapted to be of any required 45 length and may be secured to the structure in any desired manner, that shown being the preferred form. In the present instance the cables 20 and 21 are provided with nooses 22 and 23, this arrangement being provided when 50 the cables can be attached to stumps but it is to be understood that any other desired attaching means might be substituted in place of the nooses and that the cables might be secured to any suitable fixed object other than 55 stumps.

Mounted between the arms 14 and 15 adjacent the axle structure 10 and positioned for turning movement is the member 24 which is secured to the hub structure 25 that protrudes through the arm 14. Extending through the hub structure 25 is an arm 26 that is adapted to facilitate the turning of the member 24 and which is of a length sufficient to provide considerable leverage. A cable 27 is secured to the outer ends of the pull bar 18 and is 60 directed around the member 24. Preferably the cable 27 is looped once around the member 24 so as to secure a tight or snubbed connection thereto. In the present instance the ends of the cable 27 are directed through holes 65 provided in the outer ends of the pull bar 18, there being two or more of these holes so that the cable will be woven back and forth in order to provide a snubbing effect. It is apparent that movement of the arm 26 will cause 70 the pull bar 18 to pivot about the point 19. Between the pivot point 19 and the ends of the pull bar 18 a series of holes 28 are provided. Woven back and forth through these holes 75 are the cables 29 and 30, this woven connection 80 producing a snubbed connection between the pull bar and said cables 29 and 30. If desired these attaching cables may be directed to the stumps to be pulled but I have found it preferable to use the construction depicted 85 in the drawing wherein the cables are secured to a ring such as 31. Secured to the ring 31 are cables 32 and 33 which have nooses 34 and 35 at their outer ends, it being understood that any other attaching means might 90 be substituted in place of said nooses. The construction depicted is used when two stumps to be pulled are positioned closed together but it is to be understood that if there is only one stump to be pulled either the noose 95 34 or 35 would be secured to some fixed object and the remaining noose would be attached to the stump to be pulled.

In operation the anchoring members are secured to fixed objects such as the stumps depicted in the drawings and the cables 32 and 33 are attached to the stumps to be pulled in the manner described. Then the cables 29 and 30 are woven or laced through the holes 28 until the are in taut position. It is preferable that the pull bar 18 be disposed angularly to the arms 14 and 15 in order that a longer pull may be obtained before the adjustment of the devices are necessary. It is apparent that when the pull bar is disposed 105 110

angularly one of the cables 29 and 30 will be shorter than the other. With the parts arranged in this position force is exerted on the arm 26 on the side on which the pull bar 18 is at greater angularity with respect to the arms 14 and 15. The force exerted on the arm 26 will be transmitted through the member 24 and the cable 27 to the pull bar 18 and thence through either the cable 29 or 30 to the ring 31, it being apparent that as soon as a slight movement occurs the shorter of the two cables 29 and 30 will become slack. Such movement will exert tremendous force in the cables 32 and 33 which will act to extract the 15 stump.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A device of the class described including an axle structure having wheels, a pair of spaced supporting arms extending from said axle structure in one direction, a pull bar mounted for pivotal movement about one end of said supporting arms, means for turning said pull bar carried by said supporting arms in juxtaposition to said axle structure, means connecting said pull bar and said turning device, anchoring means for said axle structure and supporting arms, and attaching means 40 carried by said pull bar.

2. A device of the class described including an axle structure having wheels thereon, spaced supporting arms extending from said axle structure in one direction, a pull bar having its mid-point pivotally mounted between said supporting arms at one end thereof, means providing leverage for turning said pull bar, means mounted on said supporting arms in juxtaposition to said axle structure connecting the ends of said pull bar with said turning means, anchoring means for said axle structure and said supporting arms, and attaching means having snubbing attachment with said pull bar comprising a pair of cables attached to each side of the pivot for said pull bar adjacent the pivotal mounting thereof.

3. A device of the class described including an axle structure having wheels thereon, spaced supporting arms extending from said axle structure in one direction, a pull bar having its mid-point pivotally mounted between said supporting arms at one end thereof, means providing leverage for turning said pull bar, means mounted on said supporting arms in juxtaposition to said axle structure

connecting the ends of said pull bar with said turning means, anchoring means for said axle structure and said supporting arms, and means for connecting said device to the stump to be pulled including a pair of cables having the ends thereof woven through a plurality of holes provided in said pull bar on each side of the pivotal mounting thereof, said cables being attached to a ring, and securing means carried by said ring.

4. A device of the class described including a wheel bearing axle structure, a supporting structure comprising parallel arms extending from said axle structure in one direction in spaced relation with each other, a pull bar having substantially the midportion in the extent thereof pivotally mounted between the free ends of said parallel arms, a shaft extending through said parallel arms in juxtaposition to said axle structure, a wheel mounted on said shaft between said parallel arms, a cable having the end portions thereof secured to the end portions of said pull bar and having the intermediate portions thereof passed about said wheel, a bar extended through the upper end of said shaft whereby said shaft may be rotated to act on said cable whereby to pivot said pull bar about the pivotal mounting thereof, and attaching cables having end portions secured to said pull bar adjacent the pivotal mounting thereof.

5. A device of the class described including a wheel bearing axle structure, a supporting structure comprising parallel arms extending from said axle structure in one direction in spaced relation with each other, a pull bar having substantially the midportion in the extent thereof pivotally mounted between the free ends of said parallel arms, a shaft extending through said parallel arms in juxtaposition to said axle structure, a wheel mounted on said shaft between said parallel arms, a cable having the end portions thereof secured to the end portions of said pull bar and having the intermediate portions thereof passed about said wheel, a bar extended through the upper end of said shaft whereby said shaft may be rotated to act on said cable whereby to pivot said pull bar about the pivotal mounting thereof, attaching cables having end portions secured to said pull bar adjacent the pivotal mounting thereof, one of said parallel arms having a portion extended rearwardly of said axle structure, and a connecting member secured to said extended portion and attached to a fixed structure whereby to resist movement of the structure carried by said wheel bearing axle.

6. A device of the class described including a wheel bearing axle structure, a supporting structure comprising parallel arms extending from said axle structure in one direction in spaced relation with each other, a

pull bar having substantially the midportion in the extent thereof pivotally mounted between the free ends of said parallel arms, a shaft extending through said parallel arms 5 in juxtaposition to said axle structure, a wheel mounted on said shaft between said parallel arms, a cable having the end portions thereof secured to the end portions of said pull bar and having the intermediate portions thereof passed about said wheel, a bar extended through the upper end of said shaft whereby said shaft may be rotated to act on 10 said cable whereby to pivot said pull bar

about the pivotal mounting thereof, attaching cables having end portions secured to said pull bar adjacent the pivotal mounting thereof, a ring to which the opposite ends of said cable are secured, and connecting cables each having one of the end portions thereof secured to said ring, one of said connecting cables having the free end thereof secured to a fixed member and the other of said cables having the free end thereof secured to the member to be operated on. 15

In testimony whereof I affix my signature.
LOUIS FREY.
